ATTORNEY

UNITED STATES PATENT OFFICE

FREDERICK SCHWEIGERT, OF NEW YORK, N. Y.

INTERCHANGEABLE HAMMER

Application filed April 17, 1930. Serial No. 445,109.

This invention relates to new and useful improvements in a hammer and the like.

The invention has for an object the provision of a device of the class mentioned which is of simple durable construction, dependable in use and efficient in action, and which can be manufactured and sold at a reasonable cost.

The invention proposes in combination with a hammer head or the like having a removable striking end, nail puller or the like, a tongue projecting from one of said elements and consisting of an outer portion extending completely from end to end of said element and an inner portion extending from one end to near the other end, said tongue engaging into a groove in the other of said elements, said groove having an inner portion extending from end to end of said element receiving said outer element of the tongue, and an outer portion extending from one end to near the other end leaving a bridge on said element for abutting against said inner portion of the tongue.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:—

Fig. 1 is a side elevational view of a hammer head constructed according to this invention.

Fig. 2 is a fragmentary plan view of a portion of Fig. 1, seen as though looking on the line 2—2 of Fig. 1.

Fig. 3 is a fragmentary vertical sectional view taken on the line 3—3 of Fig. 2.

Fig. 4 is a fragmentary perspective view of the striking end of the hammer head with the striking end removed.

Fig. 5 is a fragmentary perspective view of the nail puller end of the hammer head with the nail puller removed.

Fig. 6 is a perspective view of the nail puller, per se.

Fig. 7 is an elevational view as though look-

ing in the direction of the line 7—7 of Fig. 5.

Fig. 8 is a fragmentary horizontal sectional view taken on the line 8—8 of Fig. 7.

Fig. 9 is a perspective view of a modified hammer head constructed according to another embodiment of this invention.

Fig. 10 is a fragmentary horizontal sectional view taken on the line 10—10 of Fig. 9.

Fig. 11 is an end elevational view as though taken on the line 11—11 of Fig. 9, but illustrating a modified form.

Fig. 12 is a plurality of sectional views, illustrating a number of different tongue and groove constructions adapted for arrangement according to this invention.

Fig. 13 is an enlarged perspective view of a portion of Fig. 7.

The reference numeral 10 indicates generally a hammer head of any design and construction provided with a removable striking end 11 and/or a removable nail pulling end 12. Each of these ends are so constructed as to have a tongue 13 projecting from one of said elements and consisting of an outer portion 14 extending completely from end to end of said element and an inner portion 15 extending from one end to near the other end, and said tongue 13 engaging in a groove 16 formed in the other of said elements and said groove having an inner end 17 extending from end to end of said element receiving said outer element 14 of the tongue, and an outer portion 18 extending from one end to near the other end leaving a bridge 19 on said element for abutting against said inner portion 15 of the tongue.

In Figs. 1 to 6 inclusive the hammer head 10 has been shown formed with a round striking end 11 and with a conventional nail puller 12. The tongues 13 are shown projecting from both the striking end 11 and the nail puller end 12 and engaging in grooves formed in the hammer head 10. These grooves and tongues have been shown of T construction. The outer portion 14 of the tongue 13 represents the top horizontal element of the T shape, while the inner portion 15 represents the vertical arm of the T shape.

An inspection of Figs. 3 and 6 clearly illustrates that the inner portion 15 of the

tongue extends from the top of the element to near the bottom of the element as has been recited previously. The outer portion extends from end to end of the element as may be seen from an inspection of Figs. 3 and 6.

5 This construction allows the striking end or the nail pulling end to be vertically withdrawn from the groove, or to be engaged into the groove. When thus engaged into the 10 groove a portion of the tongue extends out from the bottom so that a chisel or other tool may be engaged against this portion and hammered for loosening the parts. The bridge 15 19' restrains the engagement of these parts to correct relations, that is, as shown in Fig. 1. An aperture 20 is engaged thru the elements 11 and 12, and 10, for the reception of a pin screw or the like, to lock all of these parts in place.

20 In Figs. 7 and 8 the bridge portion 19' is clearly shown to be formed of two sections adapted for moving out from their natural positions into a position hid within the body portion 10 so that the outer portion of the 25 groove extends completely from end to end for the reception of a tongue having its inner portion extending completely from end to end. This arrangement is accomplished by a finger 21 projecting from each of the sections of the bridge and extending into cavities 22 formed in the opposite sides of the groove 16. The tongue is of smaller width than the height of the bridge section so that ordinarily the bridge section is held as shown 30 in Fig. 7. A pin 23 projects from each of the fingers 21 into vertical slots 24 formed in the body portion 10 for pivotally mounting the sections 19 and allowing the sections to be lifted upward and to be swung inward 35 into the cavity 22. This clears the outer portion of the groove and a striking end or a nail puller which have tongues extending completely from end to end may be inserted. In the normal operation of this arrangement, it 40 is used in a manner similar to the preferred form just described. In the event that it is desired to remove the bridge portion 19', it is merely necessary to first lift one of the sections of the bridge portion so that the pin 23 45 is in the upper end of the slot 24 and the bridge sections are no longer in contact with one another, one being above the other. The sections are then free and can be pivoted about on pins 23 into the cavities 22 and out of the 50 grooves 16.

55 In Figs. 9 and 10 an embodiment of the device has been shown, in which a hammer head 10' has been illustrated, differing from the previous described hammer head merely in that its striking end 11' is of square construction and it is provided with a tail head 12' in lieu of the nail pulling end. Both the striking end and the tail end are provided with tongues engaging in grooves in the head portion 10' as previously described. An-

other distinguishing feature is that the tongues are of different shape than the T shape shown in the previous forms. A dove-tailed tongue 13^a has been shown for connecting the striking end 11' with the body portion 10', and a tongue 13^b having several lateral projections has been shown connecting the tail 12' with the body portion 10'. In Fig. 10, particularly, the bridge portion 19 has been illustrated for pointing out that the constructions of the tongue and grooves are similar to that shown in the preferred form.

75 In Fig. 11 another modified form of the device shown in Figs. 9 and 10 has been illustrated, which is very similar to the embodiment shown in Figs. 7 and 8. The only distinction is that it is applied to the particular shaped tongue 13^b shown in Figs. 9 and 10. A detail description is thought not necessary 80 since the parts may be easily recognized by reference to Figs. 7 and 8, in that all the parts correspond.

85 In Fig. 12 a plurality of different shaped tongues 13^b has been illustrated. These different shaped tongues have been shown particularly to emphatically point out that the particular shape of the tongue and grooves does not constitute a limitation in this invention, since various shapes may be used with 90 application to the same arrangement. Details of the arrangement of the various tongues shown in Fig. 12 is not thought necessary since it is obvious after an understanding 95 of the previous figures.

100 While I have shown and described the preferred embodiment of my invention, it is to be understood that I do not limit myself to the precise construction herein disclosed and the right is reserved to all changes and modifications coming within the scope of the invention as defined in the appended claims.

105 Having thus described my invention, what I claim as new, and desire to secure by United States Letters Patent is:—

110 1. In combination with a hammer head having a removable striking end and nail puller, a tongue projecting from one of said elements and consisting of an outer portion extending completely from end to end of said element and an inner portion extending from one end to near the other end, and said tongue engaging into a groove in the other of said elements, said groove having an inner portion extending from end to end of said element receiving said outer element of the tongue and an outer portion extending from one end to near the other end leaving a bridge portion on said element for abutting against said inner portion of the tongue, said bridge portion being made of separate sections pivotally supported, means for normally holding the bridge sections across said groove and for allowing pivoting of these sections out 115 of the groove.

120

125

130

2. In combination with a hammer head having a removable striking end and nail puller, a tongue projecting from one of said elements and consisting of an outer portion extending completely from end to end of said element and an inner portion extending from one end to near the other end, and said tongue engaging in a groove in the other of said elements, said groove having an inner portion extending from end to end of said element receiving said outer element of the tongue and an outer portion extending from one end to near the other end leaving a bridge portion on said element for abutting against said inner portion of the tongue, said bridge portion being made of separate sections pivotally supported, means for normally holding the bridge sections across said groove and for allowing pivoting of these sections out of the groove, and said means for allowing pivoting of these sections out of the groove comprising a finger projecting from each of the said sections and into cavities formed in the body portion and a pin projecting from each finger and engageable in slots formed in the said body portion so as to allow a section to be lifted and permitting both sections to be swung on said pins into the said cavities.

In testimony whereof I have affixed my signature.

FREDERICK SCHWEIGERT.
